ELECTRONIC COMPUTING CIRCUIT

Arthur W. Vance, Moorestown, N. J., assignor to
 Radio Corporation of America, a corporation
 of Delaware

Application August 29, 1942, Serial No. 456,590

4 Claims. (Cl. 235—61)

1

This invention relates generally to electronic computers and particularly to a circuit for providing an output voltage proportional in amplitude to the product or quotient of two or more applied voltages, the amplitudes of which are representative of selected values of the variables of the equation to be solved.

A thermionic tube amplifier may be considered to be a natural multiplying or dividing device, since the output voltage is proportional to the input voltage multiplied by the gain. The gain may be made to depend on the bias applied to the control electrode circuit of the amplifier tube. However, in ordinary amplifiers the relation between gain and control electrode bias is non-linear due to individual tube characteristics, power supply variations, input voltage amplitude, and frequency. It is therefore necessary to compensate for non-linearity in a variable gain amplifier before such a device may be utilized as a high accuracy electronic multiplier.

The instant invention contemplates the use of a variable gain amplifier as a multiplying device wherein the multiplicand is applied to the amplifier input as an A.-C. potential of selected amplitude and, the multiplier is applied to the amplifier control electrode as a D.-C. bias voltage of selected amplitude. The product is derived from the amplifier output circuit as an A.-C. potential having an amplitude proportional to the product of the two applied voltages. Compensation for non-linearity of the amplifier gain is accomplished by applying to the amplifier input circuit an additional A.-C. potential of a frequency different from that of the first mentioned A.-C. potential. The two frequencies are segregated in the amplifier output circuit by means of suitable filter networks, and the second, or control, A.-C. potential is rectified and applied to the amplifier input through a suitable feedback circuit to provide a compensating bias voltage. Division of selected values of the variables may be effected by adjusting the potential of the second A.-C. potential applied to the variable gain amplifier to a value proportional to a selected value of a variable representing the divisor.

Among the objects of the invention are to provide a novel and improved method of and means for multiplying or dividing electronically two or more variables applied to a thermionic tube circuit in terms of two voltages of amplitude proportional to the selected values of the variables. Another object is to provide an improved electronic computer for multiplying two quantities of which one quantity is applied to the input of a variable gain amplifier as an A.-C. potential,

2

and the other quantity is applied as a D.-C. potential to control the gain of the amplifier. Still another object of the invention is to compensate for non-linearity in the gain of a variable gain amplifier by utilizing a control signal, of a frequency substantially different than the A.-C. signal which is applied as a multiplicand to the amplifier input, for deriving through a feedback circuit a D.-C. control potential which is applied to the amplifier as an automatic gain control voltage. A further object of the invention is to provide an indicator for the computer described heretofore which will directly indicate the product of the two applied voltages which are representative of the individual quantities to be multiplied.

The invention will be described in greater detail by reference to the accompanying drawing of which Figure 1 is a schematic block diagram of the invention, and Figure 2 is a schematic circuit diagram of a preferred embodiment thereof. Similar reference numerals are applied to similar elements throughout the drawing.

Referring to Fig. 1, a source of substantially constant amplitude A.-C. potential is derived from a conventional oscillator 1 having a frequency, for example of 25 kilocycles, and applied to the input circuit of a variable gain amplifier 2. The output of a second oscillator circuit 3 having a frequency, for example of 10 kilocycles, is also applied to the input circuit of the variable gain amplifier 2. The voltage amplitude of the 10 kilocycle applied signal may be varied to represent a selected value of one of the quantities to be multiplied. The output of the variable gain amplifier is applied to a constant gain A.-C. amplifier 4 which includes a conventional inverse feedback circuit 5. The output of the constant gain amplifier is applied to the input of two conventional filter circuits 6, 7, which are designed to pass 10 kilocycle and 25 kilocycle signals, respectively.

The 25 kilocycle signal, transmitted by the 25 kilocycle filter 7, is applied to a linear rectifier 8 to derive a D.-C. potential proportional in amplitude to the 25 kilocycle control signal derived from the variable gain amplifier. This control D.-C. potential is subtracted from a second D.-C. potential V_1 , derived from a source 9, having an amplitude proportional to the selected value of the second quantity to be multiplied. The difference D.-C. potential is amplified by a D.-C. amplifier 10 and applied to the variable gain amplifier 2 to control the gain thereof. The 25 kilocycle signal will therefore provide a D.-C. control potential component which will compensate

for ordinary non-linearity of the variable gain amplifier. The D.-C. voltage V_1 derived from the source 9 , will linearly control the gain of the variable gain amplifier 2 in accordance with the selected value of the voltage V_1 . The 10 kilocycle signal output of the 10 kilocycle filter 6 will therefore have a potential substantially directly proportional to the product of the 10 kilocycle input potential V_2 and the D.-C. gain control potential V_1 applied to the variable gain amplifier 2 .

In Fig. 2, the 10 kilocycle input signal is derived from a conventional thermionic tube oscillator 13 , the output of which is applied through a variable resistor 23 to the cathode circuit of the variable gain amplifier 12 . The selected value of the first variable X is adjusted by varying the variable resistor 23 to apply the 10 kilocycle signal to the cathode of the variable gain amplifier 12 , to provide a voltage which is proportional to the value of X . The 25 kilocycle signal is also applied to the cathode of the variable gain amplifier 12 through a second variable resistor 21 , which is connected in the output circuit of the 25 kilocycle thermionic tube oscillator 11 .

If the 25 kilocycle signal, applied to the cathode of the variable gain amplifier tube 12 , is of just sufficient amplitude to provide the desired automatic gain control bias voltage to be described hereinafter, the circuit provides multiplication only. If, however, division is desired, the amplitude of the 10 kilocycle signal may be divided by adjusting the amplitude of the applied 25 kilocycle signal by varying the second variable resistor 21 to provide a 25 kilocycle potential on the cathode of the tube 12 which is proportional in amplitude to the selected divisor.

A constant gain A.-C. amplifier 4 includes the first and second A.-C. amplifier tube 14 and 15 and the conventional inverse feedback circuit 5 . The output of the variable gain amplifier tube 12 is applied to the control electrode of the first A.-C. amplifier tube 14 through any suitable coupling circuit. The output of the second constant gain A.-C. amplifier tube 15 is applied to the inputs of the 10 kilocycle filter 6 and the 25 kilocycle filter 7 .

The D.-C. potential 9 , corresponding to the second variable Y , may be derived, in any convenient manner, from a D.-C. generator or battery, not shown. The desired value of the D.-C. potential is selected by a third variable resistor 19 . The selected D.-C. potential corresponding to the variable Y , and the 25 kilocycle signal transmitted by the 25 kilocycle filter 7 , are applied to a linear rectifier tube 8 , which may be a pentode operated on the linear portion of its detection characteristic. The D.-C. potential, representative of the variable Y , and the 25 kilocycle control potential are effectively subtracted in the linear rectifier 8 . The resultant D.-C. potential is further amplified in the D.-C. amplifier 10 , which comprises the first and second D.-C. amplifier tubes 20 and 30 . The output of the second D.-C. amplifier tube 30 is applied to the control electrode circuit of the variable gain amplifier tube 12 to control the gain thereof. The control potential will comprise a steady D.-C. component, proportional to the selected value of Y , and a rectified 25 kilocycle component, proportional in amplitude to the non-linearity of the variable gain amplifier and associated circuits. The 25 kilocycle component will therefore provide effective automatic gain control of the variable gain amplifier. The output of the 10 kilocycle filter 6 may be applied to any suitable indicator 17 , to

indicate directly the 10 kilocycle voltage output as a function of the product of the selected values of the variables X and Y .

In order to assure linear detection in the pentode rectifier 8 , an additional 25 kilocycle signal is applied to the input of the first constant gain amplifier tube 14 in order to obtain a relatively high 25 kilocycle control signal without applying the full 25 kilocycle signal to the cathode circuit of the variable gain amplifier 12 . Compensation for the additional 25 kilocycle signal is effected by an additional negative bias applied to the rectifier tube 8 from a battery or other source 16 .

The rectifier tube 8 is biased by the battery 16 to operate substantially as a linear rectifier. Naturally, such a rectifier is linear only over a relatively narrow range of input voltages. Therefore, the 25 kc. level applied to the rectifier has positive peaks which have values at about the same level as the bias battery 16 . The actual level variation of the 25 kc. signal is very slight since such variations only occur to provide the necessary A.-V.-C. control and the high loop gain of the system due to the amplifiers 4 and 10 requires only a small signal at the grid of the rectifier tube 8 . Also due to the relatively high gain of the D.-C. amplifier 10 , the level of the D.-C. voltage representing the variable Y is at a low value as applied to the grid of the rectifier 8 . Any non-linearity in the rectifier and in the amplifier 10 is compensated by the A.-V.-C. control provided by the 25 kc. feedback signal.

A multiplying circuit of the type described can theoretically be made to provide any degree of precision over any reasonable range, if sufficiently high voltages and power are available. From a practical standpoint, a relatively simple multiplier, of the general type described, may be built to have a range of one to one thousand in the input and output potentials, with an accuracy of the order of one part in ten thousand. The operating time necessary for the multiplication must be larger than the period of the lowest applied frequency. The multiplication time may therefore be considerably reduced by increasing the input frequencies.

Thus the invention described comprises an electronic computer, for multiplying two quantities, in which the quantities are applied respectively as A.-C. and D.-C. potentials to a variable gain amplifier, whereby the D.-C. potential controls the gain, and therefore the output potential of the A.-C. input, and the output A.-C. potential may be applied to the indicator to indicate directly the product of the two quantities. A second A.-C. input signal, of a different frequency than the first mentioned A.-C. input, is utilized to compensate for non-linearity in the gain of the variable gain amplifier by applying a control bias through a feedback circuit.

Division of the quantity represented by the applied 10 kilocycle potential may be effected by varying the amplitude of the applied 25 kilocycle potential to the cathode of the variable gain amplifier. The potential of the 25 kilocycle signal thus applied should be proportional to the selected value of the divisor. In other words, the setting of the control 23 determines the value of the dividend, the setting of the control 21 determines the value of the divisor, and the setting of the D.-C. control 19 determines the scale factor. Therefore, the equation

$$x = \frac{ab}{c}$$

may be solved in one operation, where a , b , and c are separate variables and x is the resultant.

I claim as my invention:

1. The combination of a variable gain amplifier having a cathode and a control grid, means for applying to said cathode first and second alternating potentials having different frequencies, a constant gain amplifier for amplifying the output of said variable gain amplifier, means connected to the output of said constant gain amplifier for segregating the second of said alternating potentials, means providing a unidirectional potential, means including a linear rectifier for providing a control potential proportional to the difference between said segregated and unidirectional potentials, means for applying said control potential to said control grid, and means for deriving from the output of said constant gain amplifier an alternating potential which has the same frequency as that of said first alternating potential and has an amplitude proportional to the product of the amplitudes of said unidirectional and first alternating potentials.

2. The combination of a variable gain amplifier having a cathode and a control grid, means for applying to said cathode first and second alternating potentials having different frequencies, a constant gain amplifier for amplifying the output of said variable gain amplifier, means connected to the output of said constant gain amplifier for segregating the second of said alternating potentials, means providing a unidirectional potential, means including a linear rectifier for providing a control potential proportional to the difference between said segregated and unidirectional potentials, means for applying said control potential to said control grid, and means for deriving from the output of said constant gain amplifier an alternating potential which has the same frequency as that of said first alternating potential and has an amplitude proportional to the product of the amplitudes of said unidirectional and first alternating potentials, divided by the amplitude of said second alternating potential.

3. The combination of a variable gain amplifier having a cathode and a control grid, means for applying to said cathode first and second alternating potentials having different frequencies, a constant gain amplifier for amplifying the output of said variable gain amplifier, means connected to the output of said constant gain amplifier for segregating the second of said alternating potentials, means providing a unidirectional potential, means including a linear rectifier for pro-

viding a control potential proportional to the difference between said segregated and unidirectional potentials, means for applying said control potential to said control grid, and means for deriving from the output of said constant gain amplifier an alternating potential which has the same frequency as that of said first alternating potential and has an amplitude proportional to the product of the amplitudes of said unidirectional and first alternating potentials, means for adjusting the amplitude of said first alternating potential to represent different values of a first variable, and means for adjusting said unidirectional potential to represent different values of a second variable.

4. The combination of a variable gain amplifier having a cathode and a control grid, means for applying to said cathode first and second alternating potentials having different frequencies, a constant gain amplifier for amplifying the output of said variable gain amplifier, means connected to the output of said constant gain amplifier for segregating the second of said alternating potentials, means providing a unidirectional potential, means including a linear rectifier for providing a control potential proportional to the difference between said segregated and unidirectional potentials, means for applying said control potential to said control grid, and means for deriving from the output of said constant gain amplifier an alternating potential which has the same frequency as that of said first alternating potential and has an amplitude proportional to the product of the amplitudes of said unidirectional and first alternating potentials, divided by the amplitude of said second alternating potential, and means for adjusting the amplitudes of said first and second alternating potentials and the value of said unidirectional potential to represent respectively different values of three different variables.
